[57] CLAIM

The ornamental design for a pillow, as shown and described.

DESCRIPTION

FIG. 1 is a top, front, and right side perspective view of a pillow showing my new design;

FIG. 2 is a bottom, rear, and left side perspective view thereof; and,

FIG. 3 is an enlarged top plan view thereof, the bottom being a mirror image of that shown.

FIG. 1

FIG. 2

FIG. 3
